FOOT OPERATED SWITCH

Harry J. Collins, Jr., Bayside, and Roy A. Mukai, Milwaukee, Wis., assignors to Cutler-Hammer, Inc., Milwaukee, Wis., a corporation of Delaware

Filed Mar. 17, 1961, Ser. No. 64,365

Term of patent 14 years

(Cl. D26—13)

Fig. 1

Fig. 2

Fig. 3

Fig. 4

Fig. 5

FIGURE 1 is an isometric view of a foot operated switch showing our new design;

FIG. 2 is a view in side elevation;

FIG. 3 is a top plan view;

FIG. 4 is a front end view; and

FIG. 5 is a rear end view.

The dominant features of our new design reside in the portions shown in solid black lines in the drawings.

We claim:

The ornamental design for a foot operated switch, substantially as shown and described.
